UNITED STATES PATENT OFFICE.

MARTIN F. BURNS, OF ASTORIA, NEW YORK.

DENTAL APPARATUS.

Application filed September 2, 1922. Serial No. 585,884.

To all whom it may concern:

Be it known that I, MARTIN F. BURNS, a citizen of the United States, and a resident of Astoria, county of Queens, and State of New York, have invented certain new and useful Improvements in Dental Apparatus, of which the following is a specification.

This invention relates to dental apparatus and more particularly to dental flasks and to investment holders used in casting plates, 10 bridges, inlays and other restorations.

In casting a plate, bridge or other restoration a dentist first makes a pattern in wax of the article to be cast. The pattern is then placed in an investment holder and is invested in an initially plastic and quick hardening composition. When the investment is dry or has set the wax is melted out or otherwise dissipated and the cavity is filled with 20 molten metal. The metal is forced into the cavity under pressure to effect the complete filling of the cavity. The casting is then allowed to cool and is preferably cooled slowly to prevent warping or distortion.

When the apparatus is used for casting inlays, the casting is comparatively small and therefore it is desirable to use a small investment holder. This saves investment and greatly expedites the making of the 25 casting since the wax pattern can be quickly melted out and the metal can be poured and will cool in a very short space of time.

One of the objects of the invention is to provide apparatus of the class described so 30 constructed and arranged as to expedite the making of small castings.

Another object of the invention is to provide a receptacle for dental casting apparatus so constructed as to be adapted for use 35 with a plurality of sizes of investment holders.

Another object of the invention is to provide a plurality of investment holders of different capacity and so constructed that 40 they can be used with the same receptacle.

Further objects of the invention will appear from the following description taken in connection with the drawings which form a part of this application and in which,

Fig. 1 is a top plan view of dental apparatus constructed in accordance with the invention and comprising a receptacle and an investment holder disposed therein.

Fig. 2 is an elevational view, partly in section, of the construction shown in Fig. 1.

Fig. 3 is a view similar to Fig. 2 but show-

ing an investment holder of smaller capacity mounted in the receptacle.

Fig. 4 is a view similar to Figs. 2 and 3 but showing another size of investment holder.

Fig. 5 is a top plan view similar to Fig. 1, but showing another shape of receptacle and investment holder, and

Fig. 6 is a top plan view showing still another shape of investment holder.

The invention briefly described comprises a receptacle having means such as a ledge or flange projecting inwardly therefrom for supporting an investment holder, the investment holder having a portion such as a laterally extending flange adapted to rest or seat on the supporting means of the receptacle.

Referring to the drawings, there is shown 75 a receptacle 10, tubular in form and in the embodiment shown in Figs. 1-4, substantially cylindrical in shape. The receptacle 10 is open at its two ends and has formed thereon intermediate the ends an inwardly projecting ledge or flange 11 having an opening therethrough.

The investment holder comprises a tubular member 12 having formed on one end thereof a laterally extending flange 13 adapted to rest or seat on the ledge 11 of the receptacle. 80 From the showing in the drawings it will be noted that the ledge 11 is recessed to receive the flange 13 of the investment holder, whereby the holder will be positioned or 85 centered and the upper surfaces of the ledge 11 and flange 13 will be flush.

By so constructing and arranging the receptacle and investment holder, holders of different capacity may be used in connection 90 with one receptacle. In Fig. 3 the investment holder 12^a is smaller in size or capacity and has a wider flange at its upper end thereby adapting this holder to be supported on the ledge 11 of the receptacle 10. In Fig. 95 4, the holder 12^b is still smaller in capacity and has a still wider flange adapted to rest on the ledge 11 of the receptacle.

The receptacle and investment holder may be made of any desired shape or contour and in Fig. 5 both the receptacle 20 and the investment holder 22 are elliptical in shape.

In Fig. 6 the investment holder 30 is substantially cylindrical and the investment holder has a circular flange 31 and an elliptical body portion 32.

It will be understood that the shape of

the investment holder and the size thereof to be used will depend on the shape and size of the casting to be made.

The apparatus above described is particularly adapted for use in making small castings such as dental inlays and because of the fact that relatively small investment holders can be used, the amount of investment necessary is reduced to a minimum and furthermore because of the smaller amount of investment the wax pattern can be quickly melted or dissipated and the casting can be made in a very short space of time.

15 Although certain specific embodiments of the invention have been illustrated and described, it will be understood that the invention is capable of further modification and that further changes in the construction and in the arrangement of the various cooperating parts may be made without departing from the spirit or scope of the invention as expressed in the following claims.

What I claim is:—

25 1. In combination, a receptacle having an inwardly extending flange thereon, and an investment holder having a flange at its upper end supported on said flange.

30 2. In combination, a receptacle having an inwardly extending flange thereon and disposed intermediate the ends thereof, and an investment holder supported on said flange.

35 3. In combination, a receptacle having an inwardly extending flange thereon and disposed intermediate the ends thereof, and an investment holder having a flange supported on said flange.

40 4. In combination, a substantially cylindrical receptacle having an inwardly extending flange thereon disposed intermediate the ends thereof, and an investment holder supported on said flange.

45 5. In combination, a substantially cylindrical, open ended receptacle having an inwardly extending flange thereon disposed intermediate the ends thereof, and an investment holder supported on said flange.

50 6. In combination, a substantially cylindrical receptacle having an inwardly extending flange thereon and disposed inter-

mediate the ends thereof, and an investment holder supported on said flange.

7. In combination, a substantially cylindrical receptacle having an inwardly extending flange thereon and disposed intermediate the ends thereof, and an investment holder supported on said flange. 55

8. In combination, a receptacle having means extending inwardly from its inner surface intermediate the ends thereof for supporting an investment holder and an investment holder having means for engaging said supporting means. 60

9. In combination, an open ended receptacle having means extending inwardly from its inner surface for supporting an investment holder and an investment holder having means at its upper end for engaging said supporting means. 65

10. In combination, an open ended, tubular receptacle having means extending inwardly from its inner surface for supporting an investment holder and an investment holder having means at its upper end for engaging said supporting means. 70

11. Dental apparatus comprising a receptacle having an inwardly extending ledge and an investment holder extending downwardly therefrom. 75

12. Dental apparatus comprising a substantially cylindrical receptacle having an inwardly extending ledge and an investment holder extending downwardly therefrom. 80

13. Dental apparatus comprising a substantially cylindrical receptacle having an inwardly extending ledge and a tubular investment holder extending downwardly therefrom. 85

14. In combination, a receptacle having an inwardly extending recessed flange thereon, and an investment holder having a flange supported on said flange and seated in said recess. 90

15. In combination, a receptacle having an inwardly extending ledge thereon, said ledge having an annular recess, and an investment holder supported on said ledge and positioned by said recess. 95

In witness whereof I have hereunto set my hand this 28th day of August, 1922.

MARTIN F. BURNS.
